DESIGN FOR A FOLDING RACK OR SIMILAR ARTICLE

Herman J. Fowler, Chicago, Ill.

Application January 14, 1947, Serial No. 136,145

Term of patent 7 years

(Cl. D33—8)

To all whom it may concern:

Be it known that I, Herman J. Fowler, a citizen of the United States of America, residing in the city of Chicago, county of Cook, and State of Illinois, have invented a new, original, and ornamental Design for a Folding Rack or Similar Article, of which the following is a specification, reference being had to the accompanying drawing, forming part thereof.

Fig. 1 is a front view of a folding rack or similar article, showing my new design;

Fig. 2 is a side view of same; and

Fig. 3 is a perspective view of same showing the rack in folded position.

I claim:

The ornamental design for a folding rack or similar article, substantially as shown.

HERMAN J. FOWLER.
